UNITED STATES PATENT OFFICE.

JOHN T. HENDERSON, OF COUNCIL BLUFFS, IOWA.

DESIGN FOR A BAIL-EAR.

SPECIFICATION forming part of Design No. 33,950, dated January 22, 1901.

Application filed December 10, 1900. Serial No. 39,445. Term of patent 14 years.

To all whom it may concern:

Be it known that I, JOHN T. HENDERSON, a citizen of the United States, residing at Council Bluffs, in the county of Pottawattamie and 5 State of Iowa, have invented and produced a new and original Design for Bail-Ears, of which the following is a specification.

This invention relates to a new and novel design for bail-ear members, the object being 10 to provide a neat and slightly bail-ear of peculiar conformation, insuring its ready attachment to a suitable pail or other receptacle.

In the accompanying drawings I have 15 shown in Figure 1 a top view of my bail-ear. Fig. 2 shows a side elevation, while Fig. 3 represents a central sectional view more clearly disclosing the united members forming my bail-ear.

20 As shown in the drawings, my invention comprises a dish-shaped receptacle, forming one member of my bail-ear, (marked 1,) which has its top slightly flared and is provided with the central opening 4. The lower edge 2, it 25 is noticed, of this member is flared outward

and downward. The second member, forming the remaining part of my bail-ear, comprises the dish-shaped portion 5, flared and provided with the edge 6, horizontal to the bottom of this member 5, and finally being 30 provided with the upwardly-flared and inwardly-extending edge 3, encompassing the upward flange 2, so that these two members are united, as is shown in Fig. 3. This second member 5 is imperforate. 35

In Fig. 1 I have shown a top view disclosing a view of the upper portion of the upper member 1.

Having thus described my invention, what I claim as new, and desire to secure by Letters 40 Patent, is—

The design for a bail-ear as herein shown and described.

In testimony whereof I affix my signature in presence of two witnesses.

JOHN T. HENDERSON.
